UNITED STATES PATENT OFFICE.

NORRIS ELMORE CLARK, OF PLAINVILLE, CONNECTICUT, ASSIGNOR TO ROBERT S. ALLYN, TRUSTEE, OF NEW YORK, N. Y.

EXPANDED-METAL MACHINE.

1,314,505.

Specification of Letters Patent.

Patented Sept. 2, 1919.

Application filed April 11, 1917. Serial No. 161,125.

To all whom it may concern:

Be it known that I, NORRIS ELMORE CLARK, a citizen of the United States of America, residing at Plainville, Conn., have invented a new and useful Expanded-Metal Machine, of which the following is a specification.

My invention relates particularly to mechanism for straightening and finishing an expanded metal fabric having relatively deep ribs such as shown in my Patents #1,104,476 and #1,128,659.

Such fabrics when expanded are quite likely to be more or less warped and the ribs are likely to be curved or somewhat irregular. It is my particular object by the mechanism herein shown and claimed to so treat the ribs and meshwork that the ribs will be perfectly straight and the fabric lie perfectly flat.

In its preferred form the invention contemplates the use of a series of feeding disks for engaging the ribs to feed the fabric in, a series of rolls and disks for controlling the ribs and delivering the fabric and a series of independently adjustable straightening disks for each rib of the fabric. The housings for supporting the rolls are especially designed to facilitate construction and adjustment.

Figure 1, is a plan view of mechanism embodying the improvements of my invention, one of the housings being shown in section and one of the upper trains of disks for handling one of the ribs being omitted so as to show the corresponding lower train of disks.

Fig. 2, is a side view of the same, one of the housings being omitted and the housing in the rear being shown partly in section.

Fig. 3, is a transverse sectional view showing the guides for one of the marginal ribs on the plane of the line 3—3 of Fig. 2.

Fig. 4, is a section of one of the straightening units on the plane of the line 4—4 of Fig. 2.

Fig. 5, is a horizontal sectional view of one of the upper straightening disks and its support.

Fig. 6, is a fragmentary view showing the final delivery and finishing rolls.

Fig. 7, is an end elevation and partial sectional view of one of the housings and its support.

55 The lower in-feeding disks 10 are carried

by a shaft 11 and the upper in-feeding disks 12 are carried by the shaft 13. The out-feeding rolls 14 and disks 15 are carried by the shaft 16 and the out-feeding rolls 17 and disks 18 are carried by the shaft 19. 60

The housings 20 for supporting the shafts and the straightening mechanism are supported by the upper flanges of I-beams 21. To facilitate manufacture the lower end of each housing is formed with two rows of 65 lugs 22 and 22' with transverse spaces 23 between them and inclined shoulders 24, 24' above them. The lower faces of the lugs may be finished to afford an accurate seat for the housing on the top of the I-beam. 70 Clamps 25 and 25' are adapted to fit the opposite sides of the housing and be drawn together by bolts 26 so as to draw the housing down tight against the I-beam. Opposite housings may be connected together for 75 instance, by angle irons such as 27, 28, 29, 30, 31 and 32 so as to hold the housings rigidly and also to afford supports for other parts if desired. Each shaft has at each end a box 34 movable vertically in the opening 35 in the corresponding housing. Each box has four flanges such as 36, one at each corner and the housing adjacent each box is provided with a finished seat 37 and shoulder 38 adapted to receive a finished 80 gib which also fits the finished flange 36 and adjacent vertical wall of the box so as to afford accurate vertical guides. Opposite gibs are clamped together by bolts 40 which fit loosely in recesses 41 in the housing. Each box of each lower shaft may be raised vertically by a screw 42 and each box of each upper shaft may be pressed 85 downward by a screw 43.

By making each lower box of a thickness 90 greater than the distance between its opposite seats 37, the box may be clamped by the gibs 39 and bolts 40.

A train of straightening disks or rolls 45, 46, 47, 48, and 49 is provided for each rib. 100 The two upper straightening disks for each rib are carried by longitudinally extending members made up of the two side bars 50 and 51 connected at each end by a block such as 52 which is secured by a bolt 53 to one 105 of the upper cross angle bars such as 28. Each of the straightening disks has a bearing stud 54 mounted in a yoke 55 pivoted at 56. The opposite end of the yoke has a lug 57 which projects into an opening in a 110

member 58 which is grooved on the sides to fit the side bars 50, 51. An adjusting member 59 has a screw-threaded part fitting the threaded hole in the member 58 and its 5 lower end passes freely through the lug 57 of the yoke. Collars or shoulders 60, 61 carried by the member 59 afford stops for lug 57 so that by rotating the screw 59 up or down the lug and yoke may be correspondingly adjusted so as to raise or lower the 10 rib straightening disk 45. The lower straightening disks are carried by similar yokes such as 62. The free ends of which are vertically adjustable in U-shape members 63 and adapted to be raised by adjusting screws 64.

A guide 65 may be provided in line with each of the lower disks 10 to support and direct the corresponding rib. A guide 66 20 extends from each disk 10 to the first straightening disk 47 of the corresponding train. An upper guide 67 extends from the upper disk 12 above the meshwork. A lateral guide 68 extends along the side of 25 the guide 66 so as to hold the side of the rib in place and direct the fabric as well as the rib at this point. Guides 69 and 70 similar to 66 and 67 are also preferably provided between the last straightening disk 30 49 and the delivery disk. By adjusting the upper and lower straightening disks relative to each other any irregularity in any rib may be taken out without affecting any of the other ribs.

35 The cross section of the disks will of course depend upon the cross sectional shape of the ribs of the fabric. Fig. 6 shows in full sized scale one cross sectional shape of fabric and disks. The disks 10 and 12 40 may be of the same cross sectional shape as the disks 15 and 18 but they are so adjusted as to engage the stock at the flanges of the ribs and thus effect the feeding of the fabric by engagement with the flanges. The cross 45 sectional shape of the straightening disks will be substantially the same as the disks 10, 12, 15, and 18 but the grooves in the upper disks may be slightly deeper so as to prevent the disks from binding on the tops 50 of the ribs. The delivery rolls 14 and 17 are of such a diameter as to somewhat crush the meshwork and set it in a definite plane thus removing any tendency to buckle which the meshwork may have. The disks 55 15 and 18 are of such a diameter relative to the rolls 14 and 17 that the disks do not bind upon the stock but merely serve to guide the ribs through the rolls and hold them from lateral movement in either direction 60 while the rolls 14 and 17 are setting the meshwork.

The supporting angle iron 30 may be slotted as at 71 to permit the marginal straightening roll holders to be laterally adjusted.

65 By correspondingly adjusting the lateral

positions of the marginal disks 15 and 18 it is possible to provide a lateral spreading or contracting action so as to decrease or increase the width as desired.

The shaft 11 may be provided with a 70 sprocket 75 for driving it and a chain 76 may connect the two lower shafts so as to drive the delivery rolls 14 and 17 at the same peripheral speed as the flanges of the disks 10. The upper and lower shafts may 75 be connected by gears such as shown at 77 in Fig. 1 so as to drive the upper disks as well as the lower if desired.

It will be obvious that this mechanism may be used by itself or it may be used as 80 a part of mechanism for expanding or ribbing a fabric. It will also be obvious that the fabric may be otherwise treated after delivery from the finishing rolls of this mechanism.

85 I claim:

1. In an expanded metal machine, coöperating upper and lower disks for engaging the ribs of a ribbed expanded fabric to feed the same, trains of disks for straightening 90 the individual ribs, coöperating rolls at opposite sides of the fabric engaging the meshwork between the ribs to set the meshwork in a substantially flat plane and means adjacent the bearing surfaces of said setting 95 rolls for maintaining the ribs spaced apart at definite distances.

2. In a machine for finishing ribbed fabric, two pairs of driving shafts, sets of feed disks on one pair of shafts adjusted to engage the flanges of the ribs only to feed the fabric by engagement therewith, sets of disks on the second pair of shafts arranged in line with the disks on the first pair of shafts and shaped to guide the ribs of the fabric without binding upon the stock and delivery rolls on said second pair of shafts arranged between the disks of said shafts to engage the meshwork and feed out the fabric and straightening disks arranged between said 110 pairs of shafts in line with the disks thereon for straightening the ribs.

3. In a machine for finishing ribbed fabric, two pairs of driving shafts spaced apart longitudinally of the machine, feed disks 115 mounted on one pair of shafts for engaging the ribs of the fabric to feed the same, guide disks mounted on the other pair of shafts in line with the feed disks, trains of straightening disks arranged between the feed disks 120 and the guide disks, the shape of the cross section of the straightening disks being such as to avoid binding on the tops of the ribs and delivery rolls mounted between the guide disks and adjusted to somewhat crush the 125 meshwork and set it while the ribs are prevented from lateral movement by the guide disks.

4. In a machine for finishing a ribbed fabric, a plurality of lower feed disks provided 130

- with central ribs and lateral grooves, upper disks co-acting therewith and provided with central grooves and lateral flanges adapted to grip the flanges only of a ribbed fabric
5. to feed the same, a plurality of trains of straightening disks in line with said feed disks, means for independently adjusting said straightening disks, a plurality of interfitting guide disks in line with the trains
10. of straightening disks and delivery rolls between the guide disks adjusted to engage and somewhat crush the fabric between the ribs while the guide disks prevent the ribs from spreading laterally.
15. 5. In an expanded metal machine, a plurality of longitudinally extending upper and lower bars, upper and lower freely rotatable rib straightening disks carried thereby respectively, some of said disks being adjustable independently of the other disks, means for engaging the ribs to feed the fabric into the said straightening disks and rolls for engaging the meshwork of the fabric between the ribs for delivering it from
25. the machine.
6. In an expanded metal machine, disks for feeding a ribbed expanded fabric, upper and lower sets of straightening disks for the ribs, lateral guides for the marginal ribs located between the in-feeding disks and the straightening disks, spaced rib-guiding disks and upper and lower mesh-engaging rolls at opposite sides of the fabric engaging the meshwork for feeding the fabric out.
35. 7. In an expanded metal machine, upper and lower sets of adjustable rib straightening disks, upper and lower sets of rib-guiding disks and upper and lower sets of mesh-setting rolls on the same axis with the rib-guiding disks, disposed at opposite sides of the fabric and engaging the mesh work for delivering and finishing the fabric.
40. 8. In an expanded metal machine, longitudinally extending side bars, yokes hinged be-
- tween the said side bars, freely rotatable straightening disks carried by said yokes and means for adjusting the height of said yokes and disks.
9. In an expanded metal machine, longitudinally extending side bars, yokes hinged between the said side bars, freely rotatable straightening disks carried by said yokes, means for adjusting the height of said yokes and disks, comprising laterally grooved members fitting the side bars and a screw adjustable in each member and coacting with the end of the corresponding yoke opposite its hinged end.
10. In a machine for finishing a ribbed fabric, a plurality of lower feed disks provided with central ribs and lateral grooves, upper disks co-acting therewith and provided with central grooves and lateral flanges adapted to grip the flanges only of a ribbed fabric to feed the same, a plurality of 65 trains of straightening disks in line with said feed disks, means for independently adjusting said straightening disks, delivery rolls adjusted to engage the fabric between the ribs so as to somewhat crush the same, 70 guides for the ribs adjacent said delivery rolls and means for driving the delivery rolls at substantially the same peripheral speed as the flanges of the feed disks.
11. In a machine for finishing a ribbed fabric, a plurality of lower feed disks provided with central ribs and lateral grooves, upper disks co-acting therewith and provided with central grooves and lateral flanges adapted to grip the flanges only of a 80 ribbed fabric to feed the same, a plurality of trains of straightening disks in line with said feed disks, means for independently adjusting said straightening disks, and means for feeding the fabric away from the 85 straightening disks.

NORRIS ELMORE CLARK.
